T. W. MILTON

STACK POLING AND GUY PAINTING DEVICE

Filed Jan. 12, 1925

Patented Jan. 12, 1926.

1,569,521

UNITED STATES PATENT OFFICE.

THOMAS W. MILTON, OF EAST ST. LOUIS, ILLINOIS.

STACK POLING AND GUY-PAINTING DEVICE.

Application filed January 12, 1925. Serial No. 2,051.

To all whom it may concern:

Be it known that I, THOMAS W. MILTON, a citizen of the United States, residing at East St. Louis, in the county of St. Clair, 5 State of Illinois, have invented certain new and useful Improvements in Stack Poling and Guy-Painting Devices; and I do hereby declare the following to be a full, clear, and exact description of the invention, such as 10 will enable others skilled in the art to which it appertains to make and use the same.

This invention relates to new and useful improvements in devices used in connection with the painting of stacks, and the guy 15 wires thereof.

In painting a stack, and especially the ordinary high metal stack, it is necessary to suspend a block and tackle on the upper end of the stack, to which tackle is connected the seat or boatswain's chair for the painter. To suspend the block and tackle it is necessary to engage a hook over the upper edge of the stack, and in the ordinary method now employed, light poles, to which 20 is connected the hook, are pushed up along the side of the stack until the hook is above the stack, when the operator lowers the poles to permit the hook to engage the edge of the stack. This method requires the services of several men, and approximately an 25 entire day. It is to overcome this difficulty that the present device has been designed. The device has for its object to carry a pole, on which is disposed the hook, up a guy 30 wire of the stack until the hook is sufficiently high above the stack to engage thereon when the pole is lowered. The pole is carried on a motor propelled carriage, which is driven up the guy wire, said carriage also 35 being provided with means for distributing oil, grease, or paint on the guy wire as said carriage moves upwardly and downwardly 40 on the guy wire.

Other objects and advantages will be apparent from the following description when taken in connection with the accompanying drawings.

In the drawings:

Figure 1 is an elevation of a stack and guy wire, showing the invention in the act of applying the hook.

Figure 2 is an enlarged vertical longitudinal sectional view through the carriage.

Figure 3 is a vertical transverse sectional view through the carriage, on the line 3-3 of Figure 2.

Figure 4 is an elevation of the stack and invention showing the hook engaged with the stack.

Figure 5 is a fragmentary detail of the upper end of the arm 20, showing the hook 21.

Referring particularly to the accompanying drawing, 10 represents the upper portion of a stack, and 11 the guy wires thereof.

Arranged to travel up and down on the guy wire 11 is a carriage 12, which consists of the upper and lower hinged sections 13 and 14, arranged respectively above and below the wire, and having therein the wire 70 engaging wheels 15 and 16, the latter of which are driven by the electric motor 17, also mounted in the casing. On the rear portion of the top section of the casing there is formed a pivot support 18 in which is pivotally mounted the angle portion of the pole 19, the longer arm 20 of which has means, such as the laterally directed hook 21, for supporting the hook 22, which is to be engaged over the upper edge of the stack 80 10, while the shorter arm 23 is provided with a weight 24 which maintains the pole in an approximately vertical position, while the carriage is traveling upwardly on the guy wire, and whereby said pole will be in no danger of striking the stack and dislodging the hook from the pole. On the other side of the pole, at a short distance above the weighted arm 23, is a short arm 25, to which is connected one end of a cord or wire 90 26, and which is arranged to rock the pole upwardly to position the hook 22 over the upper edge of the stack, when the cord or wire 26 is pulled. After such disposition of the pole and hook, the carriage is permitted to slide down the guy wire to a sufficient distance to release the hook 21 from the hook 22, and permit the hook to remain suspended or engaged on the stack. Engaged over the lower portion of the hook, which hook is substantially S-shaped, is a cord or cable 27, to one end of which the workman attaches his block and tackle, and upon pulling on the other end of the cable 27 the block and tackle may be elevated to the upper end of the stack, after which the pulled end of the cable is anchored to some point at the base of the stack. The workman then pulls the boatswain's chair up to the desired height. The motor of the carriage receives current from any suitable source, over the conduit 28.

100

105

110

The upper portion of the carriage carries a receptacle or socket for receiving a paint or grease container, which discharges its contents on the guy wire, as the carriage is moved upwardly and downwardly thereon. The socket is shown at 29.

The pintle ends 15' of the wheels 15 are supported in the vertical slots 31, of the vertical side walls of the upper section of 10 the carriage. Slidably supported on the said side walls, in straddling relation to the upper wheels 15, are the U-shaped members or yokes 33, the lower ends of the legs of which rest or bear on the said pintle ends 15 of the wheels. Pivotaly supported in each end of the upper portion of the carriage, and extending longitudinally toward the center thereof, are the arms 34, the free ends of which support the cup 36, in which is 20 disposed the lower end of a coil spring 35. On the upper end of the spring is a similar cup 36', on the upper side of which bears the tension screw 37 engaged through the upper wall of the carriage, and by means 25 of which said arms may be swung downwardly to cause the wheels 15 to bear firmly on the upper side of the guy 11, in cooperation with the drive wheels 16, therebelow, to permit more efficient traction on the guy, 30 and the effective movement of the carriage upwardly on the guy. By means of this arrangement it is possible to use the carriage on guys of different diameters.

The pivotal portion of the pole 19 is arranged to engage with a stop lug 30, on the carriage, to prevent the pole from swinging outwardly beyond a vertical position, under the influence of the weighted arm 23, thereby preventing engagement of the hook 40 with the side of the stack and possible dislodgement of the hook from the pole, while the carriage and pole are moving upwardly.

While I have shown and described the carriage as being driven along a guy wire 45 by means of an electric motor, I wish it understood that, in the event electric cur-

rent is not available, any suitable and well known means may be used for propelling the carriage.

What is claimed is:

1. A device for placing a suspending hook on the upper end of a stack to be painted comprising a carriage arranged to be driven up a guy wire of a stack, a pole on the carriage arranged to support a hook, and means for moving the pole into such position with relation to the stack that the hook will be engaged with the stack when the carriage and pole are withdrawn therefrom. 55

2. A device for placing a painter's hook 60 on a stack comprising a motor driven carriage arranged to move upwardly and downwardly on a guy wire of a stack, a pole pivotally mounted on the carriage and having gravity means for maintaining the pole 65 in upright position, means on the pole for supporting a hook in position to be engaged on a stack, and means for moving the pole against the force of the gravity means for placing the hook on the stack. 70

3. A device for placing a suspending hook on the upper end of a stack comprising a track extending from the ground to a point adjacent the top of the stack, a self-propelled vehicle arranged to run on the track, 75 and means on the vehicle for supporting a suspending hook and positioning said hook on the stack.

4. A device for placing a suspending hook on the upper end of a stack comprising a 80 self-propelled carriage having a guy receiving channel therethrough, driving means in the carriage engaged with the guy, friction means in the carriage engaged with the guy, movable arms, means actuated by the arms 85 and engaged with the friction means for urging said friction means into engagement with the guy, and a tensioning means engaged with the arms for moving the latter.

In testimony whereof, I affix my signature. 90

THOMAS W. MILTON.
